CLAIM

The ornamental design for a lid for a disposable cup, as shown and described.

DESCRIPTION

FIG. 1 is a top perspective view of the lid for a disposable cup showing my new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof, the left side elevational view being identical thereto.
